UNITED STATES PATENT OFFICE.

CHARLES W. CONNER, OF INDIANAPOLIS, INDIANA, ASSIGNOR TO ONE-PIECE BIFOCAL LENS COMPANY, OF INDIANAPOLIS, INDIANA, A CORPORATION.

APPARATUS FOR GRINDING AND POLISHING LENSES.

1,162,039.

Specification of Letters Patent. Patented Nov. 30, 1915.

Application filed December 11, 1911. Serial No. 665,066.

To all whom it may concern:

Be it known that I, CHARLES W. CONNER, of Indianapolis, county of Marion, and State of Indiana, have invented a certain useful 5 Apparatus for Grinding and Polishing Lenses; and I do hereby declare that the following is a full, clear, and exact description thereof, reference being had to the accompanying drawings.

10 The object of this invention is to improve the construction and operation of apparatus for grinding, polishing or finishing bifocal lenses so as to insure absolute accuracy in the operation, and to enable the tool to 15 grind either of the two surfaces on the same side of the lens or lens blank.

One feature of the invention consists in means for mounting a button holding pin in two different positions, one position for 20 treating the reading surface of the lens and the other for treating the distance surface of the lens. It is understood that the lens thus treated is concave, a central circular surface constituting the reading surface and a 25 surrounding annular surface constituting the distance surface. For treating the central or reading surface the pin is held in a vertical position preferably and for treating the surrounding distance surface the pin is 30 held in an oblique position substantially perpendicular to said surface. Therefore, this feature of the invention consists in means for holding the button holding pin in positions perpendicular substantially to the various surfaces of the lens to be treated. 35

Another feature of the invention consists in providing an arm on the free end of which said pin is mounted, and the other end is widened and pivotally mounted by spring- 40 pushed and adjustable pivots located at the opposite sides thereof so as to prevent oscillatory or lateral movement of the pin, but permit the free end of said arm and the pin to be moved upward away from the work. 45

The nature of the invention will be understood from the accompanying drawings and the following description and claims.

In the drawings, Figure 1 is a side elevation of the machine, the pin carrying arm 50 being shown in an elevated idle position by dotted lines. Fig. 2 is a plan view of the machine, part of the table being broken away. Fig. 3 is a section on the line 3-3 of Fig. 2. Fig. 4 is a vertical section 55 through the upper part of the apparatus on

the line 4-4 of Fig. 2. Fig. 5 is a plan view of the end of the arm carrying a pin when the pin is in a vertical position. Fig. 6 is a front elevation of the same showing the oblique position in full lines and the vertical 60 position in dotted lines. Fig. 7 is a plan view of the lens blank which is ground or polished by this machine.

A stand 10 carries a table 11, to the underside of which a motor 12 is secured from 65 which a belt 13 runs over pulley 14 on the vertical driving shaft 15, mounted at its lower end in the bracket arm 16 which extends down from the bottom of the table, and at its upper end mounted in suitable 70 bearings 17 extending through the table 11 and the plate 18, which is on top of the table and secured thereto by the screws 19 and 20.

The upper end of the shaft 15 is tapering 75 to receive the flaring shank 22 of the lens holder 23, which holds the lens blank 24, while it is being treated. The tapering connections of the parts 15 and 22 extend through the center of the lens holder. A pair of posts 25 and 26 extend upward from 80 the plate 18. The post 25, see Fig. 3, carries the pointed screw 27, while the other post 26 carries a hollow screw 28 in which a spring 29 lies and said spring projects into a hollow pointed pivot member 30. On said 85 pointed pivot holder and the pivot screw 27 a triangular pin holding arm 31 is mounted, as shown in Fig. 3, so that said arm can be oscillated from the horizontal or vertical position. The outer ends of the rear portion 90 of the arm 31 have central holes 32 to receive the points. The forward end of the arm 31 carries a head or plate 33, which has a vertical face when the arm is in a horizontal position, as shown in Fig. 4. To one 95 side of the head 33 the pin holder 34 is secured by the clamping screw 35. The pin holder 34 has a central opening through it at 36 for the insertion of the pin 37, and the other end of the holder 34 is split forming two ears 38, which are clamped together by the bolt 39. In this manner the pin 37 is clamped in the holder and the holder is 100 adjustable on the head 33 so that the pin can be given at least two positions, as shown in Fig. 6. The pin holder 34 is moved to either of these two positions and then clamped. The pin is double-pointed so that the lower point enters the concave upper surface of a 105 grinding or polishing button 40, see Fig. 4, 110

and holds it in place accurately during the revolution of the lens blank 24, and in that way the surface is ground or polished. Bifocal lenses are, with this mechanism, made by finishing one side of a blank, which is circular and concave, as shown in Fig. 4, and on this concave side two surfaces are formed; a central, circular surface, which is ground and polished by the button 40 with the pin 37 in its vertical position, as shown by dotted lines in Fig. 6; and said central surface of the lens blank is surrounded by a spherical surface and that is ground and polished by the button when the pin 37 is in the inclined position, as shown in Fig. 6. When the button is as shown in Fig. 4, it is grinding or polishing the outer of the two surfaces. Hence, the pin need be held or adjusted in only two positions, but these positions must be extremely accurate and the grinding button held positively in the desired positions, so that the surfaces will each be accurately formed and the line of division between the two surfaces will be true.

25 I claim as my invention:

1. Apparatus for grinding and polishing bifocal lenses including rotatable means for holding the lens, a button adapted to be placed upon the lens for grinding and

polishing the same, a pin for holding said button in proper position on the lens, an arm pivoted so that the free end thereof will be vertically oscillatory over the lens holder, and means on the free end of the arm for mounting said button holding pin so that said pin may be adjustable in a plane at right angles to the lens holder and when adjusted said pin can have only vertical movement.

2. Apparatus for grinding and polishing lenses including rotatable means for holding the lens, a vertically oscillatory arm with a flat-faced head and movable to position over said lens holder, a button for grinding or polishing the lens, a button-holding pin, a pin-holding clamp through which said pin extends, and means for pivotally mounting and adjustably clamping said clamp to said flat face of the arm, whereby the pin may be held in either a vertical or oblique position.

In witness whereof, I have hereunto affixed my signature in the presence of the witnesses herein named.

CHARLES W. CONNER.
